LOCKER HANDLE PULL

Bob G. Harrell, St. Louis, Mo., assignor to The Jackes-Evans Manufacturing Company, St. Louis, Mo.

Filed Mar. 31, 1972, Ser. No. 240,331

Term of patent 14 years

Int. Cl. D8—06

U.S. Cl. D8—148

FIG. 1 is a perspective view of the locker handle pull showing my new design;

FIG. 2 is a side elevational view of the locker handle pull shown in FIG. 1;

FIG. 3 is a front elevational view of the locker handle pull shown in FIG. 1;

FIG. 4 is a top plan view of the locker handle pull shown in FIG. 1;

FIG. 5 is a bottom plan view of the locker handle pull shown in FIG. 1; and

FIG. 6 is a rear elevational view of the locker handle pull shown in FIG. 1 as seen through the door of the locker.

The broken lines in FIGS. 2—6 are for illustrative purposes only.

I claim:

The ornamental design for a locker handle pull, as shown and described.
